(57) CLAIM

The ornamental design for a massage appliance, as shown and described.

DESCRIPTION

FIG. 1 is an oblique view a massage appliance showing our new design;

FIG. 2 is a side elevation view thereof showing the front side thereof;

FIG. 3 is side elevation view thereof, showing the back side thereof;

FIG. 4 is a side elevation view thereof, showing the left side thereof;

FIG. 5 is side elevation view thereof, showing the right side thereof;

FIG. 6 is a top plan view thereof; and,

FIG. 7 is a bottom plan view thereof.

The dash-dash-dash-dash type broken lines shown in the drawing are included for the purpose of illustrating environmental structure, and form no part of the claimed design. The dot-dash-dot-dash type broken lines shown in the drawings define the boundaries of the claimed design.

Shading lines are to show contours rather than surface ornamentation.
